UNITED STATES PATENT OFFICE.

HARRY J. SCHMITT, OF BROOKLYN, NEW YORK, ASSIGNOR TO WILLIAM R. NOE & SONS, A COPARTNERSHIP, OF NEW YORK, N. Y.

DESIGN FOR A BASE FOR ELECTRIC LAMPS.

Application filed May 7, 1926. Serial No. 17,601. Term of patent 7 years.

To all whom it may concern:

Be it known that I, HARRY J. SCHMITT, a citizen of the United States, residing at Brooklyn, in the county of Kings and State of New York, have invented a new, original, and ornamental Design for a Base for Electric Lamps, of which the following is a specification, reference being had to the ac-

companying drawing, forming part thereof, in which the figure is a view in perspective showing my new design.

I claim—

The ornamental design for a base for electric lamps, as shown.

HARRY J. SCHMITT.
